**PAPER FEED AND TENSIONING DEVICE FOR
USE IN ARTICLE WRAPPING MACHINES**

Warren T. Hansen, East Moline, and Milton A. Werteheimer, Rock Island, Ill., assignors to Gellman Manufacturing Co., Rock Island, Ill., a corporation of Illinois

Filed Feb. 21, 1964, Ser. No. 346,566
7 Claims. (Cl. 53—228)

Our invention relates to new and useful improvements in a Paper Feed and Tensioning Device for Use in Article Wrapping Machines.

In our experience in the art of automatic wrapping machines, such for example as shown in United States Letters Patent No. 2,853,841 dated September 30, 1958, we have found that during the wrapping process undesirable folds, curls or creases develop in the wrapping paper. Such folds, curls or creases of the wrapping paper often result from the fact that as the paper web is folded beneath the article from the latter's trailing side, the weight of the article on the paper web as it is moved imposes a slight drag on the web, resulting in the leading edge portion of the web forming a fold, curl or crease. We have also found that due to moisture as well as constantly changing temperatures, the wrapping paper may develop undesirable curls, waves, or crimps and that unless the same are removed, the article will not be perfectly sealed during the wrapping process, with the result that moisture and air will be admitted into the wrapped package. If the wrapped article is of a perishable nature, such as food products, it is apparent that such imperfect seal will result in deterioration or spoilage of the article.

It is a principal object of our invention to provide a simple yet effective and positive means for accomplishing the object of taking out of the wrapping paper all unevenness, creases or curling before the wrapped article reaches the sealing station.

Other objects will appear hereinafter.

The invention consists in the novel combination and arrangement of parts to be hereinafter described and claimed.

The invention will be best understood by reference to the accompanying drawings showing the preferred form of construction, and in which:

FIG. 1 is a fragmentary side elevational part sectional detail view of a wrapping machine incorporating the invention;

FIG. 2 is a side elevational, part sectional view of the reverse side of that shown in FIG. 1;

FIG. 3 is an elevational view, partly in section, similar to FIG. 1, but showing the parts thereof in different positions;

FIG. 4 is a top perspective view of the feed and tensioning mechanism embodied in our invention;

FIGS. 5 to 7 inclusive are schematic views of different fold operations effected by the feed and tensioning mechanism.

The several objects of our invention are accomplished by the preferred form of construction shown in the accompanying drawings.

In this connection the article wrapping and sealing machine as shown in the aforesaid patent includes a main frame 10 which supports a cutting mechanism 11 comprising a movable blade 12 and a stationary bed plate 13. The film or web of paper from a roll of paper passes over this bed plate 13 beneath the knife 12. An elevator structure is indicated at 14, shown in FIG. 4 in perspective. It is on this elevator that the article to be wrapped is moved in a manner shown in the aforesaid patent. The article moving means constitutes no part of the present

2

invention. Any conventional or approved moving means may be employed.

The elevator 14 is supported for vertical movement by standards 15 and, as in the case of the structure shown in the aforesaid patent, this elevator is moved to a position where the paper web will be wrapped thereabout in a manner to be presently explained.

Referring particularly to FIGS. 1 to 4 inclusive, the elevator comprises mounting brackets 16 arranged in parallel spaced relation with respect to each other and between which is arranged a receiving platform or plate 17. Bearing blocks 18 are secured to the brackets 16, and journaled between these blocks 18 and supported thereby for rotation are shafts 19 arranged in the same horizontal plane and in parallel spaced relation with respect to each other. Arranged on the shafts 19 are grooved pulleys 20. Connecting the grooved pulleys 20 of one shaft 19 to the grooved pulleys 20 of the other shaft 19 are elastic bands 21 similar to O-rings. The upper runs 21' of the bands 21 operate above a plate 22 slotted as at 23 to expose such runs 21' to a sheet of wrapping paper.

Above the bearing blocks 18 and supported by the brackets 16 is a second set of blocks 24. Extending between these blocks 24 and journaled therein is a pair of shafts 25 arranged in the same horizontal plane and in parallel spaced relation with respect to each other and above the plane of the shafts 19.

The shafts 25 likewise have a plurality of pulleys 26 mounted thereon and the pulleys are connected together by elastic bands 27 similar to the bands 21. The lower runs 28 of these bands 27 operate through slots 29 formed in a plate 30 similar to the plate 22. Both of these plates, 22 and 30, are supported in any suitable manner from the brackets 16.

Additional bearing blocks 31 provide bearings for the end portions of the shafts 32 and 33 arranged in parallel relation with respect to each other and in a plane above the shafts 25. Mounted on the shafts 32 and 33 are knurled rollers 34. Connecting these rollers are belts 35 having transverse ribs 36 which engage the knurls of the rollers 34, whereby to afford a positive engagement between the belts 35 and the surfaces of the roller 34, thereby to eliminate any slippage between these parts.

The upper run 37 of the belts 35 is exposed above slots 38 formed in the plate 17 which is supported from the brackets 16 by angle bars 40.

Fixedly secured to the shaft 32 is a gear 41 which meshes with a gear 42 on one of the shafts 25. The gear 42 meshes with a gear 43 fixed to one of the shafts 19. Upon rotation of the gear 41 in a clockwise direction, the belts 35 which extend transversely of the plate 17 will rotate in a clockwise direction as will the bands 21. The bands 27 will rotate in an anticlockwise direction—in other words, the lower runs of the bands 27 and the upper runs of the bands 21 will both rotate in the same direction as that of the upper runs of the belts 35.

On the shaft 32 is mounted a sprocket gear 44 which, by means of a sprocket chain 45, is connected to a sprocket gear 46 fixedly mounted on a shaft 47 journaled in a bearing plate 48 supported by the adjacent bracket 16.

On a shaft 47' is mounted a sprocket gear 49 (FIG. 2). The sprocket gear 49 by a sprocket chain 50 is connected to a sprocket gear 51 mounted on a shaft 52 supported by the bearing block 31.

The shaft 52 is rotated by certain driving mechanism (not shown) of the article wrapping machine. On the shaft 47' is mounted a sprocket gear 55. A sprocket chain 56 is operatively connected to the sprocket gear 55. The sprocket chain 56 passes over spaced rollers 57.

As will be apparent from viewing FIG. 1 and comparing the parts thereof with the same parts as shown in

FIG. 3, the sprocket gear 46 is in engagement with the lower loop 53 for reasons more fully hereinafter explained. When such sprocket gear 46 is not in operative engagement with the lower loop 53 of the sprocket chain 56, such sprocket chain 56 extends loosely from its sprocket gear 55. On the other hand, when the sprocket gear 46 is in engagement with the loop 53, the sprocket chain 56 becomes tight to transmit power to the gear 46.

The operation of our paper feed and tensioning device is schematically illustrated in FIGS. 5 to 7 inclusive. FIG. 5 illustrates the elevator in an upper position to dispose the lower runs 28 of the bands 27 and the upper runs 21' of the bands 21 in position to receive therebetween the paper web W of a length of wrapping paper. The end 58 of the web is releasably positioned between a pair of holding rollers 59 which function to hold the end 58 until the article is, by means of a follower, moved from a final fold position. The rollers 59 may be operated to effectuate such releasable holding of the end of the web by any suitable means, such for example, a cam 59' acting to move one roller into web-holding position with respect to the other roller.

Prior to the movement of the elevator to a lower position, the blade 12 will have operated to sever the web. Such lower position of the elevator is illustrated in FIG. 6, where it will be seen that the upper runs 37 of the belts 35 are in line with a receiving platform P which supports the article 60' to be wrapped. The paper web will extend downwardly from holding rollers 59 and between the bands 21 and 27. As the article to be wrapped is moved from the platform P onto the plate 17 as disclosed in the aforesaid patent, it engages the paper web W and draws the free end portion 60 therebeneath as shown in FIG. 6. The elevator will now move upwardly in the manner disclosed in the aforesaid patent, and as it reaches its upper position, the paper web, while remaining beneath the article, will be folded over the article as shown in FIG. 7, the end 58 of the web still being held by the holding rollers 59.

A suitable follower 61 is now brought into operation to move the partially wrapped article 60' to the supporting plate 62.

When the elevator reaches its upper position, the sprocket gear 46 will engage the lower loop 53 of the sprocket chain 56, conditioning the chain 56 taut, so that an operative driving connection is effected between the sprocket gear 55 and the sprocket gear 46. This operative connection and operation of the chain 56 through the chain 45 and its associated sprocket gears, transmits rotation to the belts 35 and, through the medium of the gears 41, 42 and 43, rotation to the bands 21 and 27. The rotation of the bands 21 and 27 effects the feeding of the paper web therebetween. This takes place upon the initial operation of the machine. The belts 35 rotate at a greater speed than the movement of the package by the follower 61. Inasmuch as the upper run 37 of the belts 35 is in contact with that portion of the paper web beneath the bottom of the article, it will be apparent that that portion of the web will be drawn by the belts 35 across the bottom of the partially wrapped article, thus tightening the paper about the article and removing any and all folds, wrinkles, creases or curls in the paper. This function ordinarily takes place before the follower 61 has advanced the wrapped article toward the platform P. As the article is moved onto the plate 62 by action of the follower 61, the end portion 58 of the paper web will be drawn from between the rollers 59 and that portion folded beneath the package with the end portions of the web in overlapping position, in which position they are sealed by a hot plate in the manner described in our co-pending application filed on even date hereof, Serial No. 346,506.

We have described only so much of the article wrapping apparatus as we believe necessary to an understanding of our invention. Our invention principally is in the provision of the belts 35 which rotate beneath the pack-

age at a speed faster than the advancing movement of the wrapped article whereby to accomplish the aforesaid tightening of the paper about and beneath the article and at the same time removing any curls, wrinkles, folds, creases or the like. This results in leaving the underside of the paper web smooth so that when it reaches the sealing plate it will have substantially perfect contact with such plate throughout its area beneath the article, resulting in a complete and unbroken seal.

While we have illustrated and described the preferred form of construction for carrying our invention into effect, this is capable of variation and modification without departing from the spirit of the invention. We therefore do not wish to be limited to the precise details of construction set forth, but desire to avail ourselves of such variations and modifications as come within the scope of the appended claims.

Having thus described our invention, what we claim as new and desire to protect by Letters Patent is:

1. A tensioning and paper smoothing device for use in an article wrapping machine comprising

- (a) a substantially flat plate-like support on which an article is supported with a paper web extending over the top of said article and therebeneath between the article and the support,
- (b) means for releasably holding an end of the web extending over the top of said article,
- (c) movable means carried by the support in contact with the portion of the web disposed beneath the article and movable in the same plane as that of the article when moved from said support,
- (d) means for moving said article from said support,
- (e) and means for moving said movable means in said plane and in the direction of movement of the article from said support and at a speed faster than the movement of the article from said support so as to draw said paper web tightly about said article as said article is moved from said support.

2. The device of claim 1 wherein said movable means comprises a plurality of elongated belts having their upper runs arranged in parallel relation with respect to each other and beneath and in contact with the paper web beneath the article.

3. A tensioning and paper smoothing device for use in an article wrapping machine comprising

- (a) a substantially flat plate-like support on which an article is supported with a paper web extending over the top of said article and therebeneath between the article and the support,
- (b) said support having a plurality of parallelly extending spaced apart slots formed therein,
- (c) means for releasably holding an end of the web extending over the top of said article,
- (d) roller-supported belts having their upper runs operating in said slots in position to be contacted by the portion of the web disposed beneath the article and movable in the same plane as that of the article when moved from said support,
- (e) means for moving said article from said support,
- (f) and means for moving said belts in said plane and in the direction of movement of the article from said support and at a speed faster than the movement of the article from said support so as to draw said paper web tightly about said article as said article is moved from said support.

4. A tensioning and paper smoothing device for use in an article wrapping machine comprising

- (a) a substantially flat plate-like support on which an article is supported with a paper web extending over the top of said article and therebeneath between the article and the support,
- (b) means for releasably holding an end of the web extending over the top of said article,
- (c) movable means carried by the support in contact with the portion of the web disposed beneath the

article and movable in the same plane as that of the article when moved from said support,

- (d) means for moving said article from said support,
- (e) and sprocket and sprocket chain means for moving said movable means in said plane and in the direction of movement of the article from said support and at a speed faster than the movement of the article from said support so as to draw said paper web tightly about said article as said article is moved from said support.

10

5. A tensioning and paper smoothing device for use in an article wrapping machine comprising

- (a) a substantially flat plate-like support on which an article is supported with a paper web extending over the top of said article and therebeneath between the article and the support,
- (b) said support having a plurality of parallelly extending spaced apart slots formed therein,
- (c) means for releasably holding an end of the web 20 extending over the top of said article,
- (d) roller-supported belts having their upper runs operating in said slots in position to be contacted by the portion of the web disposed beneath the article 25 and movable in the same plane as that of the article when moved from said support,
- (e) means for moving said article from said support,
- (f) and sprocket and sprocket chain means for moving said belts in said plane and in the direction of movement of the article from said support and at a speed faster than the movement of the article from said support so as to draw said paper web tightly about said article as said article is moved from said support.

35

6. A tensioning and paper smoothing device for use in an article wrapping machine having an elevator movable into and from a plane to receive an article to be wrapped, said device comprising

- (a) a substantially flat plate-like support carried by and movable with the elevator and on which an article is supported with a paper web extending over the top of said article and therebeneath between the article and the support,
- (b) means for releasably holding an end of the web 40 extending over the top of said article,

45

- (c) movable means carried by the support in contact with the portion of the web disposed beneath the article when moved from said support,
- (d) means for moving said article from said support,
- (e) and means operable when said elevator is in an elevated position for moving said movable means in said plane and in the direction of movement of the article from said support and at a speed faster than the movement of the article from said support so as to draw said paper web tightly about said article as said article is moved from said support.

7. A tensioning and paper smoothing device for use in an article wrapping machine having an elevator movable into and from a plane to receive an article to be wrapped, said device comprising

- (a) a substantially flat plate-like support carried by and movable with the elevator and on which an article is supported with a paper web extending over the top of said article and therebeneath between the article and the support,
- (b) means for releasably holding an end of the web extending over the top of said article,
- (c) movable means carried by the support in contact with the portion of the web disposed beneath the article when moved from said support,
- (d) means for moving said article from said support,
- (e) and sprocket gear and chain means operable when said elevator is in elevated position for moving said movable means in said plane and in the direction of movement of the article from said support and at a speed faster than the movement of the article from said support so as to draw said paper web tightly about said article as said article is moved from said support.
